UNITED STATES PATENT OFFICE.

FREDERICK F. GAINES, OF SAVANNAH, GEORGIA.

COMBINATION BUFFER DRAFT-ARM AND SILL-REINFORCEMENT.

1,074,709.

Specification of Letters Patent.

Patented Oct. 7, 1913.

Application filed December 17, 1912. Serial No. 737,190.

To all whom it may concern:

Be it known that I, FREDERICK F. GAINES, a citizen of the United States, residing at Savannah, Georgia, have invented a certain new and useful Improvement in Combination Buffers Draft-Arms and Sill-Reinforcements, of which the following is a full, clear, and exact description, such as will enable others skilled in the art to which it applies to make and use the same, reference being had to the accompanying drawings, forming part of this specification, in which—

Figure 1 is a plan view of a portion of a car underframe, and showing my improved draft arm, buffer and sill reinforcement combined with the bolster, center sills and end sill of the underframe. Fig. 2 is a vertical section taken approximately on the line 2—2 of Fig. 1. Fig. 3 is a front elevational view of the combination buffer, draft arm and sill reinforcement. Fig. 4 is a transverse section taken approximately on the line 4—4 of Fig. 2. Fig. 5 is a transverse sectional view taken approximately on the line 5—5 of Fig. 2.

My invention relates generally to new and useful improvements in car underframes, and more particularly to a combination buffer, draft arm and sill reinforcement, the same being formed in one piece, preferably by casting, and arranged and combined with parts of the car underframe so as to provide a pocket for the draft rigging, and to materially strengthen that portion of the underframe immediately adjacent to the draft rigging, and further to provide a solid and substantial arrangement or device for transferring buffing stresses from the striking plate and dead block, to the body bolster where said stresses are distributed throughout a comparatively large area of the underframe.

One of the principal objects of my invention is to provide a pair of draft arms which are integrally connected and constructed so as to overlie the bolster and engage the center sills and sub-sills, and to provide a pocket between the forward portions of the draft arms, which pocket receives the draft rigging.

A further object of my invention is to provide a construction which partially embraces the central portion of the car end sill, thereby securely tying same to the underframe, and further to form a dead block and striking plate integral with the forward ends of the draft arms.

To the above purposes my invention consists in certain novel features of construction and arrangement of parts hereinafter more fully described and claimed.

Referring by numeral to the accompanying drawings, 10 designates the center sills of an underframe, 11 the sub-sills, 12 the end sill, 13 the flooring and 14 the body bolster, all of which parts are of ordinary or well known construction.

The draft arms which form the main body portion of my improved device are substantially L-shaped in cross section throughout their length, each comprising a vertically disposed web 15 and a horizontally disposed flange 16. The vertically disposed webs 15 engage the inner faces of the center sills 10 and the horizontally disposed flanges engage the under surfaces of said sills. The draft arms are connected to the sills in any suitable manner, preferably by means of bolts 17 which pass through said sills and through the webs 15 and flanges 16. Formed integral with the rear ends of the draft arms are depending lugs 18, which, when the device is applied to the underframe, bears directly against the ends of the sub-sills 11. The draft arms are united by an integral, horizontally disposed web or plate 19, and also by integral, transversely disposed webs 20. The draft arms are of sufficient length to extend a substantial distance toward the center of the car beyond the body bolster 14, and at the point where the draft arms overlie said bolster the undersides of said arms and the plate 19 are recessed so as to form shoulders 21, against which the front and rear edges of the top flange of the bolster engages. The draft arms are rigidly fixed to the bolster in any suitable manner, preferably by means of vertically disposed bolts 17a, which pass through the sills 10 and through the flanges 16 and top flanges of the bolster. The plate or web 19 in front of the shoulders 21 just described occupies a plane slightly above the plane occupied by the rear portion of said plate, and in front of said shoulders the vertical webs 15 are extended downward to form comparatively deep side walls 22, the same being provided with pockets or recesses 23 in their inner faces to accommo-

100
105
110

date parts of the draft rigging (not shown). Horizontally disposed flanges 24 are formed integral with the lower edges of the walls 22, and fixed to these flanges are the ends of 5 transversely disposed draft rigging supports 25.

The forward ends of the webs 15 are united by a transversely disposed web or plate 26, which, when the device is properly 10 applied for use, engages directly against the rear side of the end sill 12, and formed integral with the forward ends of the draft arms is a transversely disposed plate 27 which engages directly against the front 15 face of the end sill. The ends of this plate 27 are reinforced by bosses 28, the same being perforated in order to receive the ends of truss rods 29 which extend in the usual manner from one end sill to the other. 20 The construction just described not only provides very substantial washers for the ends of the truss rods and prevents the nuts from pulling into the end sill, but also ties the entire car together from end to end 25 through the draft arms and sill reinforcements and said truss rods.

Formed integral with the lower portion of the plate 27 is a horizontally disposed plate 30 from the end portions of which 30 depend plates 31. Strengthening webs 32 are formed integral with the plates 27 and 30, and combined therewith to form a dead block, and formed integral with the outer ends of these strengthening webs is a vertically disposed web 33 which constitutes a striking plate. Detachably secured to the lower ends of the plates 31 is a draw-bar carry iron 34.

Formed in the forward portions of the walls 22 in front of the recesses 23 therein are horizontally disposed slots 35 which receive the ends of the transverse key utilized for connecting the rear end of the draw-bar to the draft rigging yoke.

In my improved construction it will be noted that the two draft arms are formed in a single piece, and that when applied for use they extend a substantial distance beyond or inside of the body bolster, thereby 45 relieving the car frame of concentration of stresses at the point where the center sills pass the body bolster, and such arrangement reduces to a minimum the liability of breakage of the center sills at a point immediately adjacent to the body bolster.

The forward ends of the draft arms are united by an integral dead block and striking plate, and the space between the forward portions of the draft arms is arranged 60 so as to form a substantial draft rigging housing. By forming the dead block and striking plate integral with the forward ends of the draft arms, a very strong, solid and substantial structure is provided, which 65 is effective in transferring buffing stresses

directly to the body bolster where they are distributed to all the sills of the under-frame.

Where my improved device is used in connection with wooden cars and truss rods 70 the ends of the latter are anchored or connected directly to the ends of the dead block, thereby effectively distributing all pulling strains and tying the entire car underframe from end to end. 75

The transversely disposed plates 26 and 27 at the forward end of the device engage the front and rear sides of the end sill, thereby providing a strong and substantial connection between the underframe and end 80 sill, which will be effective in reducing damage done by shifting loads, which, under ordinary conditions, frequently tear out the end sill and end of the car. The depending lugs or brackets 18 at the rear ends of 85 the draft arms bear directly against the ends of the sub-sills, thereby providing a construction which materially increases the distribution of buffing shocks and stresses to the sill members of the underframe. 90

It will be readily understood that minor changes in the size, form and construction of the various parts of my improved combination buffer, draft arm and sill reinforcement can be made and substituted for those 95 herein shown and described without departing from the spirit of my invention, the scope of which is set forth in the appended claims.

I claim:

1. As a new article of manufacture a car underframe member cast in a single piece and comprising a pair of sill and bolster-engaging draft arms, end sill engaging walls between the forward ends of said 105 draft arms a draft rigging housing, a dead block and a striking plate.

2. As a new article of manufacture a car underframe member cast in a single piece and comprising a pair of sill and bolster-engaging draft arms, a dead block, a striking plate and sub-sill engaging brackets, all 110 of which parts are cast integral.

3. In a car underframe member, a pair of sill and bolster-engaging draft arms formed 115 integral with each other, sub-sill engaging brackets integral with the rear ends of said arms, the forward portion of the vertical walls of which arms are extended downward and recessed to form a draft rigging 120 housing, and a combined dead block and striking plate integral with the forward ends of said arms.

4. In a device of the class described, a pair of sill and bolster-engaging draft arms, 125 which are substantially L-shaped in cross section, web plates integral with and connecting said draft arms, the forward portions of the vertical walls of which arms are extended downward and recessed to form a 130

draft rigging pocket, sub-sill engaging brackets integral with the rear ends of said draft arms and a combined dead block and striking plate integral with the forward ends of said draft arms.

5. In a car underframe member, a pair of integrally connected sill and bolster-engaging draft arms, the undersides of which are recessed to receive the car body bolster, a pair of transversely disposed web plates connecting the forward portions of said arms, which web plates are adapted to engage the end sill of a car underframe and sub-sill brackets integral with the rear portions of said draft arms.

6. In a car underframe member, a pair of integrally connected sill and bolster-engaging draft arms, a dead block integral with the forward end of said draft arms, the end portions of which dead block are provided with openings adapted to receive the ends of truss rods and a pair of sub-sill engaging brackets, integral with the rear ends of said arms.

7. In a car underframe member, a pair of integrally connected sill and bolster-engaging draft arms, a pair of sub-sill engaging brackets integral with the rear ends of said arms, a dead block integral with the forward end of said draft arms, the end portions of which dead block are provided with openings adapted to receive the ends of truss

rods, and a striking plate integral with the dead block.

8. In a car underframe member, a pair of integrally connected sill and bolster-engaging draft arms, the rear portions of which overlie the body bolster sub-sill engaging brackets integral with the rear ends of said arms, depending walls integral with the forward portions of said draft arms, and a pair of transversely disposed plates integral with the forward portions of the draft arms for engaging the end sill of the car underframe.

9. In a car underframe member, a pair of integrally connected sill and bolster-engaging draft arms, the rear portions of which overlie the body bolster sub-sill engaging brackets integral with the rear ends of said arms, depending walls integral with the forward portions of said draft arms, a pair of transversely disposed plates integral with the forward portions of the draft arms for engaging the end sill of the car underframe, and a combined dead block and striking plate integral with the forward ends of said draft arms.

In testimony whereof I hereunto affix my signature in the presence of two witnesses, this ninth day of December, 1912.

FREDERICK F. GAINES.
